SWIMMING DEVICE

Harold H. Wener, Stoughton, Wis.

Application January 19, 1942, Serial No. 427,235

7 Claims. (Cl. 9—21)

The invention relates generally to devices for facilitating swimming and more particularly to devices to be attached to the legs of a swimmer to increase the propelling effect of each stroke of the legs.

The general object of the invention is to provide a novel device of the foregoing character which attains a maximum propelling effect on the forward stroke of the leg, and offers a minimum resistance to the water on reverse movement of the leg through the water.

Another general object is to provide a device of the foregoing character which is light in weight, easy to put on, and does not interfere with the natural movement of the legs in swimming.

More specifically, it is an object to provide a device of this character which comprises a series of sets of plates, each set comprising a plurality of plates overlapping when closed to present a minimum of resistance to the water, and spreading to form a fragment of cone extending around the front, outside and back of the leg, the sets being graduated and increasing in size toward the upper part of the leg so that each set attains a maximum effectiveness.

Other objects and advantages will become apparent from the following description, taken in connection with the accompanying drawing, in which:

Figure 1 is a front view of a device embodying the features of the invention and showing it attached to the leg of a swimmer.

Fig. 2 is a top plan view of the device and showing the parts in open position.

Fig. 3 is a top plan view but showing the parts in closed position.

Fig. 4 is a vertical section taken on the line 4—4 of Fig. 2.

While the invention is susceptible of various modifications and alternative constructions, I have shown in the drawing and will herein describe in detail, the preferred embodiment, but it is to be understood that I do not thereby intend to limit the invention to the specific form disclosed, but intend to cover all modifications and alternative constructions falling within the spirit and scope of the invention as expressed in the appended claims.

A device embodying the features of the invention is adapted to facilitate swimming. To this end it is so constructed that it may be strapped to the lower leg and provides plates which spread outwardly on a forward stroke so that a large propelling force may be exerted by the swimmer.

On the return stroke of the leg the plates collapse upon each other around the leg so as to offer as little resistance as possible in the passage through the water. A device of this character adds considerable speed to swimming and is also of great use in treading water.

As illustrated herein, the device comprises generally a harness adapted to fit around and to be firmly held in place on the lower leg of the wearer. Secured to the harness is a series of sets of plates, the plates of each set being swingably supported by the harness so that they may swing outwardly into a semi-conical form around the leg. Thus when a forward stroke of the leg is made, the pressure of the water swings the plate outwardly, the extent of such swinging being limited by a flexible member to hold the plates at an angle to the leg. On the return stroke the plates collapse toward the leg, with the plates of each set overlapping each other. The various sets of plates are of graduated size with the smallest plates near the bottom of the leg and the largest plates at the upper end so that all sets of plates will effectively exert a propelling force in the water. The spacing of the sets is preferably such that each set overlaps the set immediately below. Thus plates of relatively great radial length may be utilized and the effective area thereof is large.

In the preferred embodiment of the invention, the harness, which is adapted to fit around the lower leg, comprises a plurality of vertical straps 10. Preferably such straps are four in number and are located at the inside, the back, the outside, and the front of the leg. At the top and bottom these straps are connected by bands 11 and 12, the band 11 extending around the leg just below the knee and the band 12 being located at the ankle. The bands 11 and 12 are preferably provided with snap fasteners 13 so that they may be opened to facilitate placing the device on the leg. Since the pressure exerted on the forward stroke is generally upward along the leg, the harness is further held in place by a strap 14 connected at its ends to the lower ends of the inside and outside straps 10 and extending under the instep. The strap 14 if desired may be provided with a snap fastener 15 to facilitate putting the device on the leg.

As mentioned above, the device includes a plurality of sets of plates adapted to swing outwardly on a forward stroke and also arranged to collapse around the leg on a return stroke. Each set comprises a plurality of plates 20 arranged to spread in a somewhat conical forma-

tion extending from the rear of the leg around the outside and to the front. Thus no part of the plates extend between the legs to interfere with the action of the swimmer. The plates of each set are fragments of a sector of a circle, the inner and outer edges thereof being concentric arcs. Preferably the arc of the inner edge of each plate is such that it approximately fits the leg when the plates are extended. With plates of this shape they may open out to form a portion of a cone around the leg, as illustrated in Figs. 1 and 2, and may interfold in overlapping relation with one another rather compactly about the leg, as illustrated in Fig. 3. Preferably the plates are in adjoining relation and overlap slightly, as indicated at 21, when they are open so that when spread or flaring outwardly they will constitute the equivalent of a solid piece. The plates are preferably made of a pliant material such as sheet aluminum, Lucite, or the like. Each plate is slightly bowed so that it will conform to the curvature of the adjacent plates to produce the conical shape. In the drawing I have illustrated four such plates as constituting each set. The plates at the front and rear of each set have their outer corners rounded, as at 22, to avoid a sharp corner.

The various sets of plates are graduated in size with the smallest set near the ankle and the largest set adjacent the knee. Thus each set of plates will attain maximum effectiveness in its propulsive effort since the lower sets will not materially prevent the set above it from gaining a proper grip on the water.

As mentioned above, the plates are adapted to swing outwardly on a forward or propulsive stroke of the leg and are adapted to collapse around the leg on the return stroke. For such movement of the plates they are swingably supported at their inner edges by means carried by the harness. In the preferred form, such means comprises a cord, wire, or the like 23 extending from the rear of the leg around the outside thereof to the front and secured to the straps 19 of the harness. The plates may be attached to the wire 23 by means of rings 24. Thus the plates have a loose pivotal or swingable connection with the wire so that they may move freely as desired.

Each plate is restricted in its outward movement so as to be retained in the most effective position. Preferably the plates are held so that when flared outwardly they occupy a position roughly at 15° to the straight out position. To this end each plate is provided with a flexible member, such as a cord or chain 25 or the like, attached at its outer end to the outer edge of the plate and at its inner end to the harness. Preferably the flexible members 25 are located at the front, outside, and rear straps 18 of the harness and have their inner ends attached thereto. To simplify the construction, the flexible members 25 at their inner ends are attached to the straps 18 at the point where the wire 23 is secured, except for the flexible members 25 of the lowermost set, in which case these members 25 are secured to the side straps at the point where the ankle strap 12 is secured.

In the foregoing I have referred to the forward stroke and return stroke of the leg. By forward stroke I mean the stroke which produces the forward propulsion, the stroke however actually being rearward. Correspondingly, the return or reverse stroke is forward relative to the

direction of movement of the swimmer and does not produce any propulsive effect.

In use, the wearer places the device on his leg and then secures the two snaps 13 and the snap 15. Obviously when the wearer is standing, the plates will fall into the collapsed position shown in Fig. 3. When swimming, a forward stroke of the leg causes the plates to spread into the form shown in Figs. 1, 2, and 4, and a large propulsive effort may thereby be exerted in the water. Such propulsive effort is sufficient to materially increase swimming speed. On such forward stroke, the cords 25 limit the outward flaring movement of the plates 20 to the position shown in the drawing so that a maximum propulsion effort is thereby obtained. On the return stroke of the leg, the plates 20 immediately collapse into the position shown in Fig. 3 so that there is very little drag through the water. While I have shown the plate at the front and the next adjacent plate overlapping the one immediately to the rear, and the rear plate overlapping the one immediately to the front, any overlapping arrangement may be utilized without departing from the invention.

From the foregoing, it will be apparent that I have provided a novel device for attachment to the leg of a swimmer which provides a maximum propelling effect on the forward stroke of the leg and offers a minimum resistance to the water on the reverse movement thereof. It is light in weight, easy to put on, and does not interfere with the natural movement of the legs in swimming.

I claim as my invention:

1. A device of the character described comprising, in combination, a harness to fit the lower leg, a plurality of sets of swingable plates carried by said harness, said sets being vertically spaced and graduated in size with the larger plates at the upper end, the plates of each set overlapping each other laterally when folded to lie close to the leg.

2. A device of the character described comprising, in combination, a harness to fit the lower leg, a plurality of sets of plates swingably carried by said plates, the sets being vertically spaced, the plates of each set interfolding laterally on the return stroke and being adapted to spread on the forward stroke, the plates of each set also overlapping the plates of the adjacent set on the return stroke.

3. A device of the character described comprising, in combination, a harness to fit the leg, a plurality of sets of plates swingably carried by said harness with a vertically spaced relation between the respective sets, each set comprising a plurality of plates located at the front, outside and rear of the leg and adapted to interfold laterally on the return stroke, said plates spreading outwardly on the forward stroke to provide a downwardly dished semiconical propelling member.

4. A device of the character described comprising, in combination, a harness to fit the lower part of the leg, a plurality of vertically spaced sets of plates, each set comprising a plurality of plates overlapping each other laterally when folded to lie close to the leg, means attached to the harness and swingably supporting the plates, and flexible means attached at one end to the plates and at the other end to the harness to limit the forward or outward flaring movement of the plates and thereby hold the plates of each set in adjoining relation.

5. A device of the character described comprising, in combination, a harness to fit the leg, a plurality of sets of plates swingably carried by the harness in vertically spaced relation, each set comprising a plurality of plates adapted to interfold on the return stroke and to flare outwardly on the forward stroke, and a flexible member for each plate attached at one end to the outer edge of the plate and at the other end to the harness to limit the outward flaring movement of the plates.

6. A device of the character described comprising, in combination, a plurality of sets of plates with the sets arranged in vertically spaced relation, a member for each set extending around the outside of the leg and attached to the har-

5 ness, said member swingably supporting the plates, said plates being adapted to interfold on the return stroke and to flare outwardly on the forward stroke, and means for limiting the outward flaring movement of the plates.

7. A device of the character described comprising, in combination, a harness adapted to fit the leg and comprising a pair of bands extending around the leg at the ankle and adjacent the knee, and a plurality of vertically extending strips laterally spaced around the leg and connecting the bands, a plurality of sets of plates with the sets in vertically spaced relation, and means secured to at least two of said strips 10 15 for swingably supporting the plates of each set.

HAROLD H. WENER.
